(57) **CLAIM**

The ornamental design for a mobile phone support connector, as shown and described.

DESCRIPTION

1. Mobile phone support connector

A connector enabling attachment to a base for a mobile phone support.

1.1. is a front perspective view of a mobile phone support connector showing the new design;

1.2. is a rear perspective thereof;

1.3. is a front view thereof;

1.4. is a rear view thereof;

1.5. is a left side view thereof;

1.6. is a right side view thereof;

1.7. is a top view thereof; and

1.8. is a bottom view thereof.

The broken lines shown in the drawings depict portions of the mobile phone support connector that form no part of the claimed design.

1 Claim, 8 Drawing Sheets
